ROTARY WELL DRILLING APPARATUS

Dennis L. Driscoll, Los Angeles, Calif.

Application November 11, 1935, Serial No. 49,175

2 Claims. (Cl. 255—23)

This invention relates to rotary well drilling apparatus and relates more particularly to a rotary or rotary table and its bushings and slips. A general object of this invention is to provide 5 a simple, strong and particularly effective rotary table assembly.

In the rotary method of well drilling the string of drilling tools is rotated by means of a rotary table carrying bushings which have driving engagement with a polygonal stem or kelly on the drilling string. A typical rotary table has a central opening for receiving a table bushing or master bushing. The opening of the table has a 10 square portion receiving a square part of the master bushing to provide a rotary drive for the bushing. A typical master bushing of the type now in general use has an opening with a square portion for receiving the square part of a Kelly bushing for rotating the drilling string and a 15 tapered portion for supporting slips to grip and support the drilling string when making up and breaking the joints of the string. This construction provides only four sets of rotation transmitting surfaces on the master bushing and Kelly 20 bushing for transmitting the rotative forces. These surfaces are subjected to excessive wear and as the wear increases the resultant play permits a back lash or hammering action to develop. The hammering and jarring of the parts is very 25 injurious to the entire rotary and its drive. It has been found that the rather thin walled skirt of the master bushing and the interior of the rotary table are particularly subjected to excessive wear due to increasing play, the skirt of the 30 master bushing assuming the greater portion of the load due to wearing of the parts. The square portion of a typical master bushing opening must be of substantial extent and materially reduces the extent of the tapered portion of the opening 35 for carrying the slips. The square portion of the master bushing opening being at the upper end of the bushing requires that the slips be lowered below the upper end of the master bushing when 40 arranged in place. Accordingly the handles of the slips cannot lie flat on the surface of the table and often project so that they are struck by a downwardly moving elevator endangering 45 the drillers.

Another object of this invention is to provide a rotary table assembly that provides a multiplicity of cooperating rotation transmitting surfaces on the master bushing and Kelly bushing held or maintained in proper rotation transmitting engagement thereby eliminating the 50

wearing of the various parts and back lash or play between the parts of the Kelly bushing.

Another object of this invention is to provide a rotary table assembly that includes a master bushing having an opening which may be tapered 5 to its upper end whereby the slips may have full extensive engagement with the tapered internal surface of the master bushing.

Another object of this invention is to provide the combination of a master bushing and a Kelly 10 bushing wherein a positive and strong rotation transmitting drive is provided between the master bushing and the Kelly bushing which does not materially reduce the area of the tapered internal surface of the master bushing or require 15 that the slips be lowered or set below the upper surface of the master bushing. As the slips of the present invention may be flush with or may project above the surface of the table the handles of the slips may lie flat on the table thereby 20 preventing injury of the handles and the workmen by an elevator striking the handles.

Another object of this invention is to provide a rotary table assembly comprising a master bushing and a Kelly bushing having interlocking parts 25 forming a positive rotation transmitting drive for the Kelly bushing that prevents upward movement and displacement of the Kelly bushing when under heavy torque.

Another object of the invention is to provide 30 a rotary table assembly embodying simple renewable or replaceable wear taking rotative transmitting parts.

Another object of this invention is to provide 35 a rotary table assembly of the character mentioned in which the slips may be easily and quickly assembled in and removed from the master bushing.

The various objects and features of my invention will be fully understood from the following 40 detailed description of a typical preferred form and application of my invention, throughout which description reference is made to the accompanying drawings, in which:

Fig. 1 is a top or plan view of the apparatus 45 provided by this invention showing the Kelly bushing in operative position in the master bushing. Fig. 2 is an enlarged vertical detailed sectional view taken as indicated by line 2—2 on Fig. 1.

Fig. 3 is an enlarged vertical detailed sectional view taken as indicated by line 3—3 on Fig. 1. Fig. 4 is a fragmentary horizontal detailed sectional view taken substantially as indicated by line 4—4 on Fig. 2. Fig. 5 is a fragmentary vertical detailed sectional view illustrating one of the 50 55

connections between the master bushing and the Kelly bushing taken as indicated by line 5—5 on Fig. 3. Fig. 6 is a fragmentary vertical detailed sectional view illustrating one of the connections 5 between the rotary table and the master bushing taken as indicated by line 6—6 on Fig. 1. Fig. 7 is a top or plan view of the assembly showing the slips in operative position in the master bushing. Fig. 8 is a vertical detailed sectional 10 view taken as indicated by line 8—8 on Fig. 7.

The apparatus provided by this invention includes, generally, a rotary table 10, a master bushing 11 arranged in the table 10 to be driven thereby, a Kelly bushing 12 adapted to be 15 movably locked in the master bushing 11 to cooperate with a kelly K to rotate a drilling string and slips 13 adapted to be arranged in the master bushing 11 to grip and support a string of pipe P.

The rotary table 10 is adapted to be mounted in 20 a well derrick at the upper end of a well bore to drive or rotate the drilling tools, etc. The rotary table 10 may be disc shaped in its general configuration and may be mounted and supported in any suitable or practical manner. The typical 25 means for mounting and driving the rotary table 10 illustrated in the drawings includes skids 14 carrying a base 15. The table 10 is supported on the base 15 through a suitable bearing 16 and is guided by a guide and hold-down ring 17. Ring 30 gear teeth 18 are provided on the under side of the rotary table 10 and a bevel gear 19 meshes with the teeth 18 to turn or rotate the table. The gear 19 is carried by a substantially horizontal shaft 9 suitable supported on the base 15. The 35 shaft 9 may be driven in the usual manner. The table 10 has a central vertical opening 20 for receiving the master bushing 11. The major lower portion of the opening 20 in the table 10 may be cylindrical or of substantially uniform diameter 40 throughout its length. The upper portion 20^a of the opening 20 is enlarged providing an upwardly facing shoulder 20^b on the wall of the opening. The upper surface 21 of the table 10 is preferably flat and horizontal. In accordance 45 with the invention grooves or slots 22 are provided in the wall of the portion 20^a of the opening 20. There is preferably a plurality of circumferentially spaced slots 22. The slots 22 preferably extend to the upper surface 21 of the table 50 10 and preferably have flat vertical side walls and horizontal bottom walls. One or more of the slots 22 have lateral or horizontal branches 22^a at their lower ends. I have shown a branch 22^a joining each slot 22. The branches 22^a extend 55 from the rear walls of the slots 22 relative to the direction of rotation of the rotary table.

The master bushing 11 is adapted to be assembled in the opening 20 of the table 10 to carry the Kelly bushing 12, the slips S, and other devices 60 for engaging and supporting drilling strings, etc. The master bushing 11 is preferably sectional to be more readily handled. In the particular case illustrated in the drawings the master bushing 65 11 comprises two like or complementary sections 23. The master bushing 11 is cylindrical in its general configuration and is proportioned to properly fit the opening 20 in the table 10. The upper portion 11^a of the bushing 11 is enlarged 70 to seat in the upper portion 20^a of the opening 20. The invention provides circumferentially spaced tongues or keys 24 on the bushing 11 for cooperating 75 with the slots 22. There is preferably a plurality of keys 24 on each section 23 of the bushing 11. One or more of the keys 24 on each

section 23 has a rearwardly projecting lug 24^a adjacent its lower end. The keys 24 are adjacent the upper end of the bushing 11 and are shaped and proportioned to be readily entered in the slots 22. If desired or found necessary the upper walls 80 of the slot branches 22^a may be bevelled as shown in Fig. 2 and the upper surfaces 81 of the lugs 24^a may be correspondingly tapered. After the keys 24 have been passed into the slots 22 the sections 23 may be turned to move the lugs 24^a into the branches 22^a of the slots. The invention provides wear taking blocks 60 adapted to be passed into the slots 22 between the forwardly facing sides of the keys 24 and the rearwardly facing walls of the slots to lock the lugs 24^a in the branches 22^a. The parts are preferably proportioned and related so that the upper end 25 of the bushing 11 and the upper ends of the blocks 60 are substantially flush with the upper surface 21 of the table 10 when the keys 24 and blocks 60 are properly seated in the slots 22. The walls of the slots 22 are adapted to cooperate with the sides of the keys 24 to transmit rotation from the table 10 to the bushing 11 while the blocks 60 dependably lock the lugs 24^a in the branches 22^a and thus lock the bushing against movement in the rotary table 10. There may be a sufficient number of cooperating slots 22 and keys 24 to dependably transmit the greatest torque to which the master bushing 11 may be subjected so that there is no danger of failure or breakage of the keys or the adjacent parts of bushing 11 and the table. Tapped openings 61 may be provided in the upper ends of the blocks 60 to receive lifting rods or handles.

The central vertical opening 26 of the master bushing 11 is formed to carry the Kelly bushing 12 and the slips 13. In accordance with the invention the major portion of the opening 26 has a downwardly and inwardly inclined surface or wall 27. The inclined wall 27 may extend to the upper end 25 of the master bushing 11, it being a feature of the invention that the rotative drive between the master bushing 11 and the Kelly bushing 12 does not necessitate the provision of flat vertical walls on the interior of the master bushing and is in the upper portion of the master bushing which is provided with thick strong walls. If desired, the lower portion of the master bushing opening 26 may have a downwardly and outwardly inclined wall 28. A hard wear taking insert or ring 82 may be provided in the lower portion of the opening 26 to prevent excessive wearing of the bushing 11 by drill pipe, etc. being pulled or operated through the opening. In accordance with the invention a plurality of slots 29 is provided in the wall of the opening 26. In the particular embodiment of the invention illustrated in the drawings there are four equally spaced bayonet slots 29. The slots 29 are preferably identical in size and shape. The slots 29 are in the nature of bayonet slots whose vertical arms extend downwardly from the upper surface 25 of the master bushing. The lateral arms 30 of the bayonet slots 29 are at their lower ends and may be substantially horizontal. The upper walls 84 of the slot arms 30 may be bevelled or inclined. The bayonet slots 29 are preferably comparatively large. The wall of the master bushing 11 may be chambered and provided with webs as at 31 to be light in weight.

The Kelly bushing 12 is adapted to be arranged in the master bushing 11 to rotate a polygonal drill stem or kelly K and permit longitudinal shifting of the kelly during the well drilling oper-

ations. The Kelly bushing 12 has a central vertical opening 33 shaped to shiftably pass the kelly K and shaped so that its walls have rotative driving engagement with the surfaces of the kelly. 5 In the particular case illustrated in the drawings the kelly K is substantially square in horizontal cross section and the opening 33 is correspondingly shaped. The Kelly bushing 12 is sectional preferably comprising two like sections 34. The 10 walls of the Kelly bushing sections 34 may be chambered as at 35 to be light in weight. In accordance with the invention the Kelly bushing 12 is proportioned so that its upper end 36 is substantially flush with the upper end of the master bushing 11 when properly seated in the master bushing opening 26. The peripheries or outer surfaces of the Kelly bushing sections 34 are tapered downwardly and inwardly to seat on the internal surface 27 of the master bushing 11. As 15 the internal surface 27 of the master bushing 11 is of substantial vertical extent the Kelly bushing sections 34 may have extensive seating or bearing engagement in the master bushing 11. Suitable handles 37 may be provided on the Kelly bushing sections 34 to facilitate their handling. 20

The invention provides a novel and particularly effective rotative drive and lock between the master bushing 11 and the Kelly bushing 12. The driving and inter-locking connection between the 25 master bushing and the Kelly bushing comprises spaced keys 38 on the Kelly bushing sections 34 for cooperating with the bayonet slots 29. There is preferably a plurality of keys 38 provided on each Kelly bushing section 34. The keys 38 are 30 spaced and positioned to be readily entered in the bayonet slots 29 and are preferably spaced below the upper end of the Kelly bushing sections 34 so that the upper ends 36 of the sections 34 may be substantially flush with the upper surface 25 of the master bushing 11 when the keys are properly 35 seated in the bayonet slots 29. Each key 38 has a lug 65 adjacent its lower end projecting rearwardly relative to the direction of rotation of the rotary table. The lugs 65 are formed and proportioned to enter and cooperate with the arms 30 of the slots 29. The upper surfaces 85 of the lugs 65 may be bevelled to cooperate with the inclined walls 84 to provide for the safe easy removal of the master bushing 11 as will be hereinafter described. 40

The Kelly bushing sections 34 may be individually inserted in the opening 26 of the master bushing 11 so that their keys 38 enter the bayonet slots 29 and may be turned to move the lugs 65 45 into the lateral arms 30 of the bayonet slots. Wear taking blocks 66 are then inserted in the slots 29. The blocks 66 are arranged between the forwardly facing sides of the keys 38 and the rearwardly facing walls of the slots 29 to lock the lugs 65 in the slot arms 30. Threaded openings 67 50 may be provided in the tops of the blocks 66 to receive lifting rods. The cooperation of the lugs 65 with the lateral arms 30 of the bayonet slots effectively prevents upward movement and dis- 55 placement of the Kelly bushing sections 34 when the Kelly bushing is under heavy torque and when the kelly K is raised. The lugs 38 preferably have some vertical clearance in the lateral arms 30 of the bayonet slots 29 to permit the proper wedging 60 or seating of the Kelly bushing sections 34 in the opening 26 of the master bushing 11. 65

The slips 13 are intended to be arranged in the master bushing 11 to grip and support a pipe P during the making and breaking of joints 70 in a drill stem and during other operations. 75

The slips 13 are preferably provided in a set of three or more to facilitate their easy handling. The slips 13 have tapered outer surfaces 40 for seating in the master bushing opening 26. The peripheries or outer surfaces 40 of the slips 13 5 are tapered downwardly and inwardly and are curved or convex to effectively fit and wedge against the tapered surface 27 of the master bushing 11. It is to be particularly noted that the tapered surfaces 40 of the slips 14 may be 10 of substantial vertical extent to have extensive engagement with the tapered surface 27 of the master bushing 11. In practice the wedge surfaces 40 of the slips 13 may extend throughout the lengths of the slips to have engagement with the tapered master bushing surface 27 throughout its vertical extent. The slips 13 are preferably proportioned so that their upper end portions project above the upper surface 25 of the master bushing 11 when the slips are properly 15 fitted in the opening 26. This proportioning and arrangement of the slips 13 provides for the easy convenient handling of the slips and provides for the bearing of the slips 13 in the upper thick-walled part of the bushing 11. Pivoted 20 handles 42 may be provided on the upper ends of the slips 36 to facilitate their handling. It is to be noted that the handles 42 carried on the projecting upper ends of the slips may be 25 flat on the upper surface of the table. The inner sides of the slips 13 are concave to provide a substantially cylindrical opening 43 when the slips are assembled in the master bushing 11. The opening 43 is adapted to receive the pipe P and the inner sides of the slips 13 are provided with teeth 44 for biting into and gripping the pipe P. The teeth 44 are shaped to dependably grip and support the pipe P. The slips 13 30 may be chambered as at 45 to reduce their weight. 35

It is believed that the utility and practicability of the rotary table assembly of the present invention will be readily understood from the foregoing detailed description. The keys 24 of the master bushing 11 cooperate with the slots 22 45 in the rotary table 10 to provide a dependable drive between the table and the bushing. The lugs 24^a cooperate with the branches 22^a to prevent vertical movement of the master bushing 50 in the table 10 while the blocks 60 lock the lugs 24^a in the branches 22^a. Thus the master bushing 11 is effectively locked in the rotary table. The blocks 60 take up any wear between the contacting surfaces and prevent excessive play 55 from developing. There may be a sufficient number of slots 22 and keys 24 to insure the transmission of heavy torque between the table 10 and the bushing 11 without endangering the parts. The master bushing 11 is a simple substantially cylindrical assembly that seats in the 60 cylindrical opening 20 of the table 10. The cylindrical openings of the rotary table 10 and the master bushing 11 present smaller mouths than the square openings now commonly provided in rotary tables and master bushings so that 65 there is less danger of tools, etc. falling into the well. 70

The rotary drive between the master bushing 11 and the Kelly bushing 12 does not require the provision of flat faces or a flat walled socket 75 in the master bushing 11 and, therefore, does not reduce the height of the tapered surface 27 of the master bushing. Accordingly, the tapered seat or surface 27 of the master bushing 11 may extend to its upper end to be of large extent and 75

to provide for the transmission of force between the Kelly bushing 12 or slips 13 and the master bushing 11 at the thick walled upper portion of the master bushing. The bayonet slots 29 5 and the keys 38 cooperate with their lugs 65 to form a strong positive rotative drive and dependable lock between the master bushing 11 and the Kelly bushing 12. The cooperation of the lugs 65 with the lateral arms 30 of the bayonet slots 10 29 dependably prevents upward movement or displacement of the Kelly bushing sections 34 from the master bushing when the Kelly bushing is subjected to heavy torque or upward forces while the blocks 66 retain the lugs 65 in proper 15 cooperation with the arms 30. There may be a sufficient number of keys 38 on the Kelly bushing 12 to dependably transmit rotation between the master bushing 11 and the Kelly bushing 12 without danger of breakage of the parts. The 20 Kelly bushing sections 34 and the slips 13 seating in the master bushing 11 to have their upper ends flush with or projecting from its upper end may have their handles flat against the upper surface of the table to insure safe operations at the rotary.

Following the removal of the blocks 66 from the slot 29 the Kelly bushing 11 may be easily removed from the master bushing, the inclined walls 84 and surfaces 85 cooperating to facilitate 30 the ready disengagement of the lugs from the slot arms. In withdrawing the kelly k its shoudered or enlarged lower end sometimes strikes upwardly against the lower end of the bushing 12 and the cooperation of the surfaces 85 with 35 the walls 84 allows the lugs to automatically disengage from the slot arms 30 when this occurs without danger of fracturing the lugs 65.

Having described only a typical preferred form and application of my invention, I do not wish to be limited or restricted to the specific details herein set forth, but wish to reserve to myself any variations or modifications that may appear to those skilled in the art or fall within the scope 5 of the following claims.

Having described my invention, I claim:

1. In combination, a rotary table having a cylindrical opening and a slot in the wall of the opening having a lateral branch, the upper wall of the lateral branch being inclined, a master bushing arranged in the opening, a key on the master bushing extending into the slot to form a torque transmitting drive between the table 15 and bushing, a lug on the key cooperating with the lateral branch to lock the bushing in the table, the upper side of the lug being inclined and easily freed from said upper wall, and a removable block in the slot to lock the lug in the 20 branch.

2. In combination, a master bushing for arrangement in a rotary table and having a cylindrical opening and a slot in the wall of the opening, there being a lateral branch communicating with the slot, the upper wall of the lateral branch being inclined, a Kelly bushing arranged in the opening, a key on the Kelly bushing cooperating with the slot to form a torque transmitting drive between the bushings, a lug on the 25 key cooperating with the branch to lock the Kelly bushing in the master bushing, the upper side of the lug being inclined and easily freed from said upper wall, and a removable block inserted in the slot to cooperate with the key 30 to hold the lug in the lateral branch.

DENNIS L. DRISCOLL.
